JUVENILE CHAIR

Harley H. Melzian, Detroit, Mich., assignor of one-half to W. B. Ford Design Corporation, Detroit, Mich., a corporation of Michigan

Application September 17, 1948, Serial No. 148,640

Term of patent 14 years

(Cl. D15—1)

To all whom it may concern:

Be it known that I, Harley H. Melzian, a citizen of the United States, residing at Detroit, in the county of Wayne and State of Michigan, have invented a new, original, and ornamental Design for a Juvenile Chair, of which the following is a specification, reference being had to the accompanying drawing, forming part thereof.

I claim:

The ornamental design for a juvenile chair, substantially as shown.

HARLEY H. MELZIAN.
